UNITED STATES PATENT OFFICE.

JOHN E. DAVIES, OF WAUKEGAN, ILLINOIS, ASSIGNOR TO DAVIES CAR WHEEL & MACHINE COMPANY, OF CHICAGO, ILLINOIS, A CORPORATION OF ILLINOIS.

METALLIC RAILWAY-TIE.

932,002.

Specification of Letters Patent. Patented Aug. 24, 1909.

Application filed February 29, 1908. Serial No. 418,443.

To all whom it may concern:

Be it known that I, JOHN R. DAVIES, a citizen of the United States, and resident of Waukegan, in the county of Lake and State of Illinois, have invented a new and useful Improvement in Metallic Railway-Ties, of which the following is a specification.

My invention pertains particularly to metallic railway ties which may be employed 10 as substitutes for the wooden ties now in common use; and the primary object of the invention is to provide a tie possessing greater durability and capable of more successfully fulfilling its functions than any tie 15 heretofore known; its use obviating the necessity of fish-plates and the means of fastenings now employed, thus greatly enhancing the safety and efficiency of the track-way.

20 The invention is illustrated in its preferred embodiment in the accompanying drawing, in which—

Figure 1 represents a broken plan sectional view of a railroad track built in accordance with my improvement, the section being taken as indicated at line 1—1 of Fig. 2; and Fig. 2, represents a vertical sectional view taken on the line 2—2 of Fig. 1.

In the construction shown A and B represent the ends of abutting rails of a track; C, C¹, rail-bearings forming a portion of my improved tie; D, a tie-rod joining the rail-bearings C, C¹.

Each of the rail-bearings C, C¹, comprises preferably a downwardly dished circular base e, and a rectangular shaped head-portion surmounting the base, which is provided with the longitudinal inverted T-shaped channel d, extending entirely through the head-portion, forming jaws e, e. The channel d is formed to receive the base and main portion of the web of the rail; the jaws e, e, extending over the base of the rail as shown, providing a seat for the rail. The abutting rails meet preferably in the longitudinal center of the T-shaped channel. The bearings are preferably slipped on the rails from the ends thereof, the rails being provided with a sufficient number to give the desired support. The channel d, is made slightly larger than the base and web of the rail. Into the space between the top of the base and one side of the web, I prefer to place a lining f, of any suitable sound-deadening material such as wood-fiber, or the like.

This lining f, is preferably a thin sheet of material which may be treated to withstand moisture and which may be readily bent to conform to one of the rail sides or web and the top of the corresponding bottom flange 60 of the rail. Into the space on the other side of the rail, I place the block or member g, preferably thicker than the member f; it is of course of angle-form to conform to the adjacent side of the web and top of the 65 flange of the rail. This block or member g, is also preferably treated in a solution to enable it to withstand the effects of weather. One end of the block or member g, is tapered somewhat, as indicated at g¹, to enable its 70 being easily driven into place; the member acts as a wedge to effect a close joint between the rail and the bearing.

Extending longitudinally of and preferably secured in a suitable manner to the surface of the member g, which is adjacent to the web of the rail is a strip of copper h, which will come against the web of the rails to form an electrical connection when desired. Integral with one side of the bearing, 75 is a boss or extension j, which is provided with a hole or socket to receive the downwardly bent ends of tie-rod D. The ends of the tie-rod D, are each provided with a hole as at k, (see Fig. 2) which, when the tie-rod 80 D, is in place, registers with a transverse opening in the boss j, so that a bolt or cotter-pin l, may be passed through the boss and the ends of tie-rod D, thus locking the latter in place against displacement. The bearing members C, C¹, are thus linked together 85 into pairs, thus binding the opposing bearings of the two rails together against any independent movement transversely of the track. The connection is such as to permit 90 one rail-support to settle without affecting the other rail-support injuriously. The advantage of this feature will be evident, when it is recalled that in the use of the ordinary rigid tie, when one end of the tie settles, the 95 other is thrown up, so that a rocking action is produced, which soon aggravates the injury to the road-bed.

I prefer to provide the bottom of the T-shaped channel of the supports or bearings 105 with a boss or lug m, formed integral with the bearing (see Fig. 2). The purpose of this lug m, is to prevent creeping of the rail, and the lug takes into a small depression or notch chipped or otherwise put into the un- 110

derside of the base of the rail. This notch can easily be chiseled into the rail while the track is being laid, as the notch need only be slight to accommodate the lug or boss m , 5 thus providing what may be termed an anti-creeping mechanism.

The bases of the rail-supports or rail-bearings, may be of any desired diameter, suited to the conditions of the road-bed. 10 In forming the track, the rail-supports are slipped upon the rail-bases and suitably spaced and secured by means of the wedges. The wedges may be secured against working loose by means of nails n , extending through 15 a perforation which may be provided in the walls of the rail-support or bearing and taking into the wedges or blocks g ; and as the point of the nail encounters the flange of the rail when being driven into place, it will 20 bend to one side, thus firmly holding the nail and block. After the bearings or ties are properly located, the material of the road-bed is thoroughly tamped in to fill the space in the hollow base of each rail-support, and 25 the bases of the rail-supports are buried in the road-bed, so that the supports are thoroughly anchored. Because of the symmetry of each support, there is no more tendency for the support to work in one direction 30 than, in another, with respect to the road-bed, so that the tendency of the ties always is to keep their proper positions. Of course, in the supports or bearings intermediate of the ends of the rails, the wedge blocks g , 35 need not be provided with the metallic or copper plate or strip, as this is only needed at the juncture of two rails.

It is obvious that in my improved construction no fish-plates and bolts are required for joining the ends of the rails, and 40 no spikes are required for securing the rails at their bases. It thus appears that a fruitful source of loss and danger is removed by the use of my invention, and the cost of 45 maintenance of the road is very materially decreased. Moreover, the whole construction is designed to prevent undue relative movement of the parts and to deaden the sound incident to the passage of a train. It 50 will be readily understood that with my improved tie, the time and labor required to lay a track will be materially lessened.

It will be understood that changes in details of construction within the spirit of my 55 invention may be made, and I do not wish

to be understood as limiting myself to the exact construction shown and described, but

What I wish to claim as my invention and secure by Letters Patent, is:—

1. A tie comprising a rail-support having a body-portion provided with an inverted T-shaped channel, a hollow symmetrical base diverging outwardly and downwardly from the body-portion, means integral with said body-portion and taking into the channel to 60 impinge against the rails to prevent creeping, and means whereby a pair of the supports are yieldingly linked together.

2. A tie, comprising a rail-support having a body-portion provided with a rail-receiving channel, a convex base integral with and extending downwardly from said body-portion, means integral with said support and taking into the channel and adapted to impinge against the rails to prevent creeping, 70 and mechanism removably connected with said supports whereby a pair may be yieldingly linked together.

3. A tie, comprising a rail-support having a body-portion provided with an inverted T-shaped channel, a hollow symmetrical base diverging outwardly and downwardly, a boss integral with said body-portion and provided with a socket, a tie-rod whose ends take into the sockets of oppositely placed supports, and mechanism adapted to take through the boss and the ends of said rod whereby a pair of said supports are yieldingly linked together.

4. A rail-support comprising a body-portion provided with a rail-receiving channel, a boss extending into said channel and taking against the base of the rails, and a hollow symmetrical base integral with and diverging outwardly and downwardly from 95 said body-portion.

5. A tie, comprising a rail-support having a body-portion provided with an inverted T-shaped channel, an extension on one side of said body-portion provided with a socket, 100 a hollow symmetrical base diverging outwardly and downwardly from said body-portion, and a tie-rod whose ends take into the sockets of oppositely arranged supports where they are yieldingly locked in place. 105
